UNITED STATES PATENT OFFICE.

SAMUEL KELLETT, OF SAN FRANCISCO, CALIFORNIA.

DESIGN FOR CENTER-PIECE.

Specification forming part of Design No. **8,013**, dated January 19, 1875; application filed January 2, 1875.
[Term of Patent 14 years.]

To all whom it may concern:

Be it known that I, SAMUEL KELLETT, of the city and county of San Francisco, State of California, have invented and produced a new and original Design for a Center-Piece, reference being had to the accompanying photograph, and to letters marked thereon.

My new design is in style Grecian; and consists of drop A, engraved and beaded at the base. Plain raised bands B B start from base of drop, finishing in raised scrolls at the center of figure, and Grecian leaves C C at right and left of bands. Those described forms repeat. A stem, D, separating to right and left, with bud on the end, fills the space between leaves C C. A plain bead circles inner center. A stem, E, with bell-shaped end, placed between plain bands and covered by bead-moldings, extends to outer edge of center-piece. Wing-shaped leaves F F branch from

stem on outside of bead. Triplet leaves, G G G, with scroll, and thistle-shaped bud on the end, complete this figure, which is repeated. Between these last-described stem and leaves is formed a design, H, with small leaves lying over bead, scroll-like leaves on each side, small scrolls flowing right and left, with flower I in center, extending beyond plain edge. This plain edge is a raised fillet with sunk molding.

Having thus described my invention, what I claim as new, and desire to secure by Letters Patent, is—

The design for a center-piece, as shown and described.

SAML. KELLETT.
